COMBINED BRACKET AND GRAB HANDLE

Ralph G. Rutman and Harry J. Warmkessel, both of Allentown, Pa., assignors to Mack Trucks, Inc., Plainfield, N.J., a corporation of New York

Filed Aug. 30, 1961, Ser. No. 66,550

Term of patent 14 years

(Cl. D10—8)

We claim:
The ornamental design for a combined bracket and grab handle, as shown.
